No. 804,929.

PATENTED NOV. 21, 1905.

J. CAHILL.
ROLLING SHUTTER.
APPLICATION FILED NOV. 8, 1904.

UNITED STATES PATENT OFFICE.

JOHN CAHILL, OF NORFOLK, VIRGINIA.

ROLLING SHUTTER.

No. 804,929.

Specification of Letters Patent.

Patented Nov. 21, 1905.

Application filed November 8, 1904. Serial No. 231,828.

To all whom it may concern:

Be it known that I, JOHN CAHILL, a citizen of the United States, residing in Norfolk, in the county of Norfolk and State of Virginia, have invented a certain new and useful Improvement Relating to Rolling Shutters, of which the following is a specification.

The improvement lies in the roller and the provisions for working it. Any of the ordinary styles of rolling shutter can be used with my improvement. I will describe it as applied to one of the long-approved forms, using the term "roller" to designate the set of partial rollers or pulleys which are properly spaced apart on a horizontal shaft. In the axial line of the roller I mount a relatively stationary rod on which springs are carried which engage the pulleys. When the roller, composed of the several pulleys, has by its revolution in the proper direction wound upon itself one layer of the shutter and it commences to wind the second layer, I allow the entire roller to change its position by correspondingly moving away from the building. This allows the shutter to rise and sink always from the extreme inner line of a cylinder, which varies in diameter as the shutter is wrapped around it.

In my improved construction, as in many before in use, the weight of the shutter is approximately balanced by springs. I have devised a construction in which a short sleeve is carried on the rod free to turn thereon, with a volute spring carried on each end. Thus arranged the lateral strains due to the two springs are balanced with the effect to greatly reduce the friction of the sleeve. The nearly stationary axial rod should be cylindrical at those portions of its length which carry the sleeves and may be so throughout its whole length. A screw or other suitable fastening secures the inner ends of the two volute springs to this central rod. The outer end of each spring fastens to the interior of the rim of a pulley. The sleeve must be sufficiently long to give a good bearing on the cylindrical rod within. As the hub or sleeve is limited in length, because it cannot extend longitudinally into the space traversed by the spring, there is likely to be a tendency to a skewing of the sleeve, which I resist by the bearing being of sufficient length and peculiarly fitted. I can use two or more such sleeves arranged end to end in the same roller, if required, or I can allow all the other pulleys to turn freely without any sleeve or spring.

The following is a description of what I consider the best means of carrying out the invention.

The accompanying drawings form a part 60 of this specification.

Figure 1 is a front elevation, partly in vertical section, showing the entire mechanism with the shutter nearly unrolled. A portion of the shutter is broken away. Fig. 2 is a 65 corresponding end view as seen from the left in Fig. 1. Fig. 3 shows a portion on a larger scale. It is a central vertical section corresponding to the section in Fig. 1.

Similar letters of reference indicate corresponding parts in all the figures where they appear.

A is the wall of a building.

A' is a casing secured at the sides, respectively, of the window-opening and loosely inclosing the edges of the shutter when it is drawn down into position for use.

A² represents brackets which support the mechanism, each equipped to allow a carriage to move toward and from the building 80 when required.

C C are carriages adapted to so travel and to form supports for the roller and its attachments.

C' C' are small wheels mounted on pins on 85 each carriage and capable of traveling on the brackets A². Other wheels C² C², which may be smaller, as their work is lighter, are carried on each carriage, bearing against the under side of the corresponding bracket. I 90 have shown in Fig. 2 two such wheels acting underneath.

B is a relatively stationary rod supported in such carriages and adapted to carry the weight and also to serve as an abutment for 95 the springs to resist the torsional strain. I have shown this in a tubular form, the main portion being a sufficiently stout tube, and the bearing at each end firmly held by a screw F in the U-shaped pocket C⁴, provided 100 in the corresponding carriage.

D is a sleeve turning loosely on the rod.

D' D' are extended disks or pulleys, and D² is a bridge cast in one therewith and connecting the disks at one point in the periphery. 105

M is the shutter, shown as corrugated; but it may be understood as composed of slats hinged together, as usual. The upper slat is secured by a screw N to a bridge D². There may be any ordinary or suitable mechanism 110 to facilitate the turning of the roller and the consequent raising and lowering of the shut-

ter. As shown, the shutter having its gravity nearly balanced in all positions by the tendency of the springs to uncoil is raised or lowered by the direct application of the hands of 5 an attendant.

D^3 represents wide rims constituting what I will term "barrels," one on the periphery of each disk.

- E E are the springs of sufficiently stout 10 flat steel, coiled volute after the manner of clock-springs. The inner end of each spring is secured by the screw E' to the shaft B, and the outer end of each spring is secured to the inner surface of the corresponding barrel D^3 . 15 It will be seen that there are thus two springs E E for one sleeve D. When properly wound or "charged," each spring exerts a force tending to turn the sleeve D and its attachments in the direction to lift the shutter. 20 In that respect they are coincident or identical in their action; but in another respect they exert forces which are opposed and balance each other—that is, the tendency to skew the sleeve D in its bearings on the shaft. 25 There is ordinarily a disturbing force exerted by each volute spring. Each exerts force tending to set the sleeve askew on the rod. The screws E' for the two springs should be set in accord, both on the same 30 side of the axis of motion, so that the radial force of one spring is in the same direction as that of the other spring, and being exerted at opposite ends of the sleeves the skewing strain of each balances that of the other. In 35 other words, the skewing action of one spring opposes the skewing action of the other by both urging its end of the sleeve D in the same direction equally. There is thus a lateral pressure on the sleeve; but it is uniform 40 along the entire length. There is no skewing strain.

B^2 B^2 are disks fixed by screws B^3 to the rod B. Each is nearly in contact with the outer end of the corresponding barrel D^3 and serves 45 not only to make a finish, but to keep the sleeve D and its attachments, including the corresponding spring E, in position.

I have shown two sleeves D, each with two corresponding barrels. Both sets may be 50 used with springs or one may be a dummy. In either case each will serve as a part of the roller to receive and give off the rolling shutter. There may be additional loose pulleys, dummies.

55 There is a tendency in mechanism of this kind for the rod B, with its load, the flexible rolling shutter, to be drawn inward toward the building. I resist this by a helical spring I, connecting each end of the rod B with an 60 arm A^4 , bolted on an extension of each bracket A^2 . The exteriors of the barrels D^3 , and consequently of the rollers, are not circles. An offset is made at D^4 in each barrel to a depth about equal to the thickness of the shutter, and the contour of each pulley from the

bottom of the offset is a volute curve, shown as extending about one-fourth of the circumference. It may extend farther or less. In theory the volute curve should extend quite around the pulley. The bridges extend 70 across from one pulley to the next in the deepest part of the notches thus formed, and the top bar of the shutter is secured there. To raise the shutter, the roller is slowly revolved in the proper direction, and the shutter winds on the recessed roller. The top bar of the roller is sunk just so much that when one complete revolution has been made and the roller commences to accumulate a second layer it mounts thereon without seriously disturbing the cylindrical form of the mass, and all lies smoothly and evenly in every part of each circuit. 75 80

I use the term "double-ended" as applied to the spring to mean that the ends alternate in 85 their action, the two ends being not necessarily alike in form, but being each ready to serve and actually serving at some periods as the working end and at other periods simply as the abutment for the action. 90

Modifications may be made without departing from the principle or sacrificing the advantages of the invention.

Parts can be used without others. Some of the benefits may be realized with only one 95 spring, simply omitting one of the springs E.

I include in the term "rolling shutter" any of the various forms of metal or wood partitions made in sections wound upon the roller and pendent therefrom by gravity. 100

The size and thickness of the pulleys or disks D' may be varied within wide limits.

I claim as my invention—

1. In shutter-operating mechanism having a shaft B a sleeve D turning loosely 105 thereon and provisions for turning the shaft and the sleeve with different motions, the two barrels D^3 on the ends respectively of said sleeve D and the bridge D^2 and rivet N connecting such barrels to the upper edge of 110 the shutter, combined substantially as herein specified.

2. In a shutter-operating mechanism, the combination with a rolling shutter, guiding ways, and a roller, of a spring exerting a 115 force in opposition to the gravity of the shutter, an internal rod serving as an abutment for the spring, and an interposed sleeve having a barrel serving to connect the spring and such shaft and a second spring correspondingly carried on such sleeve, arranged as shown, so that the radial force of two such springs balance each other, all substantially as herein specified. 120

3. In a shutter-operating mechanism having a shaft B, supported in carriages C C traveling toward and from the building and a series of barrels D^3 loosely supported and revoluble thereon having each an offset D^4 with the diameter increased uniformly there- 125 130

from quite around the periphery substantially as herein specified.

4. In shutter-operating mechanism, the combination with a rolling shutter, guiding-
ways, and a roller, of a spring exerting a force in opposition to the gravity of the shutter and a sleeve running loosely on such shaft carrying a barrel which constitutes a portion of the roller and a separately-formed internal shaft serving as an abutment for the spring, two carriages having each a U-shaped bearing and fastening means F for one end of such shaft, level ways for such carriages and an outside spring I near each end of the roller for aiding the movement of the roller in one direction, all arranged for joint operation substantially as herein specified.

5. In shutter-operating mechanism, the combination with a rolling shutter, guiding-

ways, and a roller with means for turning such roller to raise and lower the shutter, of springs and means for supporting the weight of the shutter thereby, two carriages having each a bearing for one end of such shaft, level ways for such carriages, and an outside spring I near each end of the roller for aiding the movement of the roller in one direction along such ways as the shutter accumulates in thickness on the roller all arranged to serve substantially as herein specified.

In testimony that I claim the invention above set forth I affix my signature in presence of two witnesses.

JOHN CAHILL.
